SOFA BED

Bernard Castro, Fort Lauderdale, Fla.

Application January 11, 1957, Serial No. 633,564

1 Claim. (Cl. 5—51)

This invention relates to an improvement in convertible beds of the general kind illustrated and described in the co-pending application for U.S. Letters Patent Serial No. 419,173, filed March 29, 1954, now Patent No. 2,829,381.

In sofa beds wherein a bed mechanism is adapted to be folded into and unfolded from a stationary frame, one troublesome problem has been how to guard or cover certain parts of the bed mechanism so that a person using the mechanism won't cut himself or his clothing or cut, tear or rip the bed mattress or sofa cushions. One part of this problem has been successfully solved in a second co-pending application for U.S. Letters Patent Serial No. 562,148, filed January 30, 1956, now Patent No. 2,818,584 in which a simple yet very efficient arrangement is illustrated and described for keeping the mattress and bed linens of a sofa-bed from being cut or torn when the bed is being folded and unfolded.

There remained, however, in sofa beds of this kind the danger and annoyance of sharp, pointed ends of the bed mechanism, particularly those ends which are in front and hence most prominent when the bed is unfolded and in sleeping position. In a bed mechanism using the improved lock shown in the first co-pending application Serial No. 419,173, now Patent No. 2,829,381, identified above, this problem is accentuated because the front end of the lock mechanism has thin narrow members which project outwardly therefrom. Since these projecting members are somewhat horn-like, they sometimes unfortunately lead to a bruised shin for an unwary person who misjudges his distance. They also sometimes gore the back seat cushion of the sofa when the mechanism is being very carelessly folded to form a sofa. Furthermore, the projecting members are apt to score or otherwise mar other pieces of furniture which they may strike accidentally when the bed is being opened. The present invention seeks to overcome these difficulties.

In accordance with the present invention the outermost corners of a bed mechanism when in unfolded position are provided with rotatable rubber guards, preferably in the form of small rubber wheels, and so positioned that a person brushing against one of these corners is protected from hurting himself or tearing his clothing by the rounded shape of the guard and its ability to rotate. Thus, instead of being impaled by a sharp point the person is gently rolled past the corner of the bed. In conjunction with these rotating guard wheels there is also provided, according to the invention, a tube-like bar which extends between the wheels at approximately the same level. This bar not only acts to brace the wheels and the side members of the bed mechanism but also complements the guard members in preventing the front end of the bed from goring the back cushion of the sofa as may occasionally happen when the bed is folded in hasty or careless manner.

A better understanding of the invention together with a fuller appreciation of its many advantages will best be gained from a study of the following description given in connection with the accompanying drawings in which:

2

Figure 1 is a perspective view of a sofa bed embodying the features of the present invention and showing the mechanism unfolded to form a bed;

Figure 2 is a slightly enlarged view of the bed shown in Figure 1 and showing it in partly folded position;

Figure 3 is an enlarged view of the front end of the bed taken as viewed from line 3—3 in Figure 1 and showing the position of the guard wheels;

Figure 4 is an enlarged view of one of the wheels as viewed from line 4—4 in Figure 3; and

Figure 5 is a view of the wheel as viewed from line 5—5 in Figure 4.

Figure 1 shows a sofa-bed 10, in unfolded position. The folding mechanism for this bed can be generally like that shown in co-pending application Serial No. 419,173, identified above. Bed 10 includes a stationary frame 11 and the folding mechanism, generally indicated at 12. Mechanism 12 includes an inner section 15 pivoted to the frame 11, an intermediate section 17 pivoted to section 15, a connecting section 19 pivoted to section 17, and an end section 21 pivoted to section 19. As will be understood from Figure 2, end section 21 is adapted to fold back over intermediate section 17 to provide the seat of a sofa on which removable cushions, not shown, may be placed. These cushions, in conjunction with the permanent back cushion 22 fixed to the vertical portion of frame 11 comprise the seating and supporting surfaces for sofa 10. A sheet-like member 24, as seen in Figure 2 overlies end section 21 and serves to protect the bed mattress 26, folded double between the bed sections and seen best in Figure 1, from dirt and dust. Member 24 is resiliently fastened along its forward end as viewed in Figure 2 closely adjacent the movable frontboard 28 in the manner described in U.S. Patent 2,752,613. The other end of member 24 is fastened to the free end of the bed in a manner to be described.

Referring to Figure 1, two lock members, generally indicated at 30, are mounted on the respective front corners of end section 21 and project forwardly therefrom. These projecting lock members 30 may present a hazard to the shins or clothing of a person who misjudges his position and will mar any other piece of furniture that they may accidentally strike when the bed is being unfolded.

In accordance with the present invention a guard wheel 32 is rotatably mounted on each respective lock member 30 and overlies the member to minimize the danger of injury to the person or articles of furniture. Thus, a person or an article of furniture brushing against the wheels 32 at either front corner of the bed is protected from injury.

As can be seen in Figure 2, the free end of bed section 21, when the bed is partly folded, is pointed toward back cushion 22. Lock members 30 at the free end of the bed section 21 are adapted to engage portions of the headboard member 33 and to squeeze bed section 21 toward section 17 with mattress 26 folded between. When the bed is completely folded these members 30 and 33 will hold the bed sections folded until it is desired to unfold them.

As members 30 are horn-like extensions which project beyond section 21, they might gore back cushion 22 if the bed were carelessly folded. Such damage is prevented by virtue of another feature of the invention. This feature of the invention comprises a bar 34 in the form of a round tube, see Figures 1 and 3, which is mounted on and extends between the lock members 30. Bar 34 is covered by the end of sheet-like member 24 which is wrapped partly around it and is attached to the spring support for the mattress. This construction provides in effect a padded front bumper.

Referring to Figures 3, 4 and 5, each wheel 32 is

rotatably mounted at 36 on an angularly bent plate 38 which, in turn, is fastened to a respective side rail 40 of the end bed section 21. Each plate 38 has the bent down portions 42 which carry between them the rotatably mounted rollers 44 of the lock members 30. These rollers cooperate with headboard member 33 in the general way described in application Serial No. 419,173, now Patent No. 2,829,381, identified above. Each end of tube 34 is flattened at 46 and is fastened at 48 to a respective plate 38.

Wheels 32 can be made of soft rubber approximately two inches in diameter and one-half inch in thickness. The relative size and shape of the other elements shown in Figures 4 and 5 can be exactly as shown.

The above description of the invention is intended in illustration and not in limitation thereof. Various changes may occur to those skilled in the art and these may be made without departing from the spirit or scope of the invention as set forth.

I claim:

A convertible sofa-bed of the character described comprising: inner, intermediate, connecting, and end bed sections serially pivoted to each other; a stationary furniture frame, said inner and intermediate sections being pivoted thereto, a bed mattress adapted to lie horizontally upon said sections when open and when said bed is closed to be folded double between said end and said intermediate sections with said end section horizontally above said intermediate section, a back cushion and two upholstered side arms fixed to said frame, a headboard member fixed to said inner section at right angles thereto, two roller-lock brackets each fixed on and projecting

from respective front corners of said end section and adapted to bear upward against said headboard member to hold said sections folded over when said bed is closed, and two guard members each fastened to respective ones of said brackets, each guard member comprising a small wheel rotatably mounted on a pin on its corresponding bracket with the rim of said wheel projecting slightly beyond the front and the side of said bracket, the end of said bracket when said bed is open being inclined slightly upward and forward with said wheel closely parallel and with said pin extending upward and backward, whereby when said bed is unfolded, a person is protected by said wheels from hurting himself against said projecting brackets, and when said bed is being folded said back cushion and upholstered side arms are protected by said wheels which are adapted to roll downward and backward in contact with said arms and to bump against said back cushion.
